CLAIM

We claim the ornamental design for the cup with lid, as shown and described.

DESCRIPTION

FIG. 1 is a perspective view from the front direction of a cup with lid showing our new design;

FIG. 2 is a perspective view from the rear direction thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view thereof, taken along line 9—9 of FIG. 3;

FIG. 10 is a cross-sectional view thereof, taken along line 10—10 of FIG. 6;

FIG. 11 is a top plan view thereof, the lid with a tab in an open position; and

FIG. 12 is a cross-sectional view thereof, taken along line 12—12 of FIG. 13 depicting the lid in an open position; and, FIG. 13 is a front elevational view thereof depicting the lid in the open position.
